LOADING OR BOXING APPARATUS

Application filed April 5, 1929. Serial No. 352,637.

This invention relates to improvements in loading or boxing apparatus, especially a machine for delivering sealed vessels, such as cans and the like to boxes or cases in which the cans are handled for storage and distribution.

An object of the invention is to provide a boxing machine by which cans are received and delivered to the boxes continuously, by means of power-operated members which move the cans without injury to the labels thereon, or other damage which might affect the value of the cans and their contents.

A further object of the invention is to provide a boxing machine which is simple but strong in construction, efficient in use, and capable of perfect control, so that it can be kept running, or stopped at any instant, in case of a mishap, to prevent scoring, denting or crushing the cans, or breakage of any of the parts of the apparatus.

Another object of the invention is to provide a boxing device designed to receive the cans in multiple lines, stopping the influx of the cans periodically and delivering a predetermined number to the box or casing, and then permitting the feeding of the cans into the machine to be resumed and to continue until the next box is put in place for the cans to be moved into it.

The nature of the invention will appear from the following description taken with the accompanying drawings, illustrating a preferred form of the invention. The disclosure, however, is explanatory only and changes may be made in the shape, size and arrangement of parts and other details without going beyond the principle of the invention or exceeding the scope thereof as the same is indicated by the broad, general meanings of the terms in which the appended claims are expressed.

On the drawings,

Fig. 1 is a side view of a machine according to my invention;

Fig. 2 is a top plan of same;

Fig. 3 is a section on the line 3—3 of Fig. 1;

Fig. 4 is a section on the line 4—4 of Fig. 1;

Fig. 5 is a section on the line 5—5 of Fig. 1;

Fig. 6 is a view of a detail;

Fig. 7 shows a view similar to Fig. 5 with the parts in a different operative position; Fig. 8 is a sectional view on the line 8—8 in Fig. 5;

Fig. 9 is a detail showing how the members presented in Fig. 8 are caused to operate.

On the drawings the same numerals identify the same parts throughout.

In the particular description of what the drawings set forth I use the numeral 1 to indicate the top, table, platform or base of the machine which is supported by legs 2 at one end and legs 3 at the other. On this platform above the legs 2, I show a receiving chute 4 for the cans which are fed into the machine; and adjacent the other extremity of the platform is an upright stop or riser 5 which cooperates with an upright part 6, adjacent the middle of the machine and separated from the stop 5 by a space substantially equal to the length of the box or case into which the cans are loaded. Attached to the rear of the platform 1 are two supports 7 which project out horizontally from the top 1 and are channeled along their inner faces to mount a slidable frame 8. This frame is designed to be actuated to engage the cans in position between the stop 5 and upright 6 and push them toward the opposite or front side of the machine; where there are a pair of arms 9 secured to the platform 1 and projecting out horizontally to provide a rest on which the boxes or cases to be filled are successively placed. The pushing of the cans forward between the stop 5 and upright 6 is intermittent, and whenever this step is performed, the cans which are fed into the machine must be presented from moving into the space between the stop 5 and member 6; or damage to the labels of the cans and other injury to the exterior thereof might occur. For this purpose I utilize a

number of blades 10 which are mounted on upright bars 11 at the back of the machine in line with the member 6. To the top of this member I may affix a guideway 12, extending rearward; and to the rear side of the platform I may attach a bracket 13, adjacent the lower ends of these bars. The upper

ends of the bars 11 are connected together by a cross piece 14 and the lower ends may be united in a manner which will be described later. The frame comprising bars 11 is caused to move forward just before the frame 8 makes its stroke, and when the bars 11 are so moved, the blades 10 are interposed between the cans which have entered the space between the stop 5 and member 6, and whatever cans are disposed in the machine outside of this space. Thus any more cans are prevented from moving past the member 6 until the frame 8 has pushed all of the cans directly in front of it into the box for the cans, which is placed on the arms 9; supported thereby on one side so as to present its open top towards the cans which are being moved into it. The platform 1 is mounted as shown in Figure 1 so that it slopes from the chute 4 towards the stop 5 in order that the cans which are fed into the chute may roll by gravity down towards the stop; and as indicated in Figures 3, 4, 5 and 6, the front edge of the platform 1 may be higher than the rear edge so as to eliminate all tendency of the cans to move forward of themselves toward the box on the arms 9.

The power for operating the machine is furnished by a suitable source; such as an electric motor 15 mounted upon one of the legs 2, and connected through suitable gearing to rotate a main shaft 16 in bearings beneath the platform 1 and extending along the length of the apparatus. This shaft transmits rocking motion to another shaft 17, mounted in suitable bearings adjacent the rear of the machine; and carrying a lever 18 connected to the frame 8, and a similar lever 19 united to the frame carrying the blades 10. These levers are designed to rock as required to actuate the frame 8 and the blades 10 in the proper order.

We will now describe the chute 4 which receives the cans as they are fed into the machine. This chute has sides 20 extending longitudinally if the base 1 and spaced apart a distance equal to the height or length of the cans which are to be loaded. These sides carry on their inner faces rests 21 spaced apart and connected with sloping ribs 22 leading to trays 23. These trays are shown as four; but this number may be varied, and so may the number of rests 21 and rails or ribs 22 to suit the capacity desired. The number of pairs of rests 21 is illustrated as three and the attendant feeding the cans into the chute may put them on each pair of these rests so that they run down along the ribs in three lines to the trays 23. A fourth line of cans can be handled by means of the top tray 23 in which the cans are placed directly. The trays 23 have sides 24 and these sides may be extended as at 25 to enable the trays to be attached to the sides 20 of the chute 4 at one end; the trays being supported

at their opposite ends by connection to the upright 6, and to similar trays 26 which extend between this upright and the stop 5 and are of course suitably secured in place. These trays 26 have rims 27 along their rear edges only, so that as the cans roll into them they pass on toward the stop 5 until these trays 26 are full. Then the slideable frame 8 pushes them forward toward the box or case on the arms 9. These trays 26 may extend from the rear side of the platform 1 toward the front as far as necessary so as to be in proximity to the open top or mouth of the case in which the cans are to be delivered; and the case may project in between the stop 5 and member 6, so as to enable the loading to be performed in the most expeditious manner. The stop 5 may carry supports 28 for the trays 26, and similar supports may be attached to the member 6 for the trays 26 and 23. The top of the platform 1 between the stop 5 and member 6 serves for the lowermost tiers of cans and no tray 26 is placed thereon in line with the lowermost tray 23, but the platform may have a rib 29 along the rear edge between the stop 5 and member 6 for the same purpose as the rear edges 27 of the trays 26. The top tray 23 may have its sides extended by means of plates or bars 30. Hence as the cans are fed into the machine they all roll down on the trays 26 and the top of the platform 1 between the stop 5 and member 6; and when the pusher frame is actuated the cans are all moved forward and pushed off the trays and platform 1; the cans of the upper tiers as soon as they leave the trays 26 resting upon and being supported by the cans below them.

The frame 8 comprises a number of transverse horizontal bars 31 at the forward end thereof; and these bars act as pusher bars to engage the rear ends of the cans when the frame 8 thrusts the cans out from between the stop 5 and member 6.

Attached to the front of the platform between the stop 5 and member 6 is a bar 32 to which are attached can guides 33. These guides have their ends secured to the bar 32 and are bent into the form shown in Figure 3; being mounted so that they are between the lowermost cans as the latter are pushed off the platform. The guides 33 may be made fast in the bar 32 by means of binding screws 34; and this bar is held on the base 1 by suitable bolts 35. On the arm 9, I may put a table plate 36 for the more efficient support of the boxes or cases into which the cans are pushed by the frame 8. The can guides 33 serve the purpose of spacing the bottom cans properly as they are pushed from the space between the stop 5 and member 6; and as these guides are rounded they make contact with each can at only one point. Hence unnecessary friction is avoided.

We have shown on Figure 1 of the drawings only the lowermost tier of cans, in dot-

and-dash lines, but of course the three trays above this tier of cans will also be filled and unloaded with the cans on the platform 1.

The part 12 attached to the top of the member 6 may be a piece of angle iron; and may have affixed to the under surface of its top a plate 37, spaced from the vertical web of this angle bar so as to provide a guideway for the cross-bar 14 at the tops of the bars 11. The lower ends of these bars are united by a cross-bar 38 carrying rollers 39. To the side of the bracket 13 may be affixed a bar 40 having cam recesses 41 and this bar may have an overturned top edge 42 providing a track for the rollers 39. Thus as the lever 19 is rocked, the blades 10 are moved toward the front of the machine; and then as the rollers 39 drop into the cam recesses 41 the blades move downward. In this movement the blades are passed across each tier of cans, first moving between the last can to reach the space between the stop 5 and member 6 and the next can of each tier on its way to this space; but out of contact with these cans. Then with the downward movement of the bars 11 as the rollers 39 reach the cam recesses 41, the blades 10 are inserted between the cans of each tier which have passed upon the member 6; and the cans behind them. The influx of cans is then stopped until the pusher frame 8 has cleared away the cans which are ready to go into the box. The lower edges of the blades 10 will, of course, be ground to an edge to make them work more easily.

The lever 19 is joined to the frame carrying the blades 10 by a link 43. The shaft 17 on which the lever 19 is mounted is received in bearings 44 at the rear of the machine, and at its lower end is provided with a pin 45, which enables it to be connected to an operating bar 46, which is moved back and forth by means of cams on the shaft 16. This bar 46 is yoke-shaped, with the shaft 16 between the arms thereof; and it has at one end a slot 47 receiving the pin 45. Between the arms of this bar is a slide block 48 (Figure 3) on the shaft 16, and the arms of this yoke-shaped bar 46 are connected at their ends by a cross-bar 49. The ends of the arms have stems 50 projecting therefrom through the cross-bar 49, these stems being encircled by springs 51 confined against the bar 49 by nuts 52 on the ends of the stems 50. On the bar 49 is a roller 53 and adjacent the other end of the bar 46 and on the side opposite to that bearing the roller 53 is another roller 57. These rollers are engaged by cams 54 and 56, respectively, on the shaft 16, the bar 46 lying between these cams. Hence as the shaft rotates the cams 56 and 54 make the bars 46 reciprocate; the cam 54 engaging the roller 57 to move this bar to the left and the cam 56 engaging the roller 53 to move the bar 46 to the right. While reciprocating

the two arms of the bar 46 slide along the top and bottom of the block 48. The cams 54 and 56 both have hubs 55, and the shaft 16 is mounted in bearings below the platform 1 shown at 58. These bearings may be anti-friction bearings; and additional bearings 59 are provided for the end of the shaft supported by the legs 2 and 3. The bar 46 carries below the slotted end thereof, a hollow projection 60 carrying a pin 61 actuated toward the pin 45 by a spring 62. This pin engages a notch 63 in the link 19 and the projection 60 carries a screw-threaded closure plug 64 by which the compression of the spring 62 can be adjusted. The pin 61 and the notch 63 are shaped so that the pin can easily slip out of this notch; but the spring will keep the pin 61 pressed into the notch, so as to connect the lever 19 with the operating bar 46 under ordinary conditions. Hence if the machine, and particularly the cams 54 and 56 are improperly operated, or if the cans are not in the right position, so that the blades 10 should strike the ends of the cans, instead of passing between the cans, or hit any other obstruction, damage will be avoided; because then the pin 61 will slip out of the notch 63 and by reason of the presence of the slot 47 the bar 46 will move without rocking the lever 19. Under certain conditions the connecting piece 49 will yield by reason of the presence of the springs 51, if there should be improper operation of the parts tending to throw the bar 46 in the opposite direction or to operate in the wrong manner the lever 19.

The connections between the lever 18 and the shaft 16 are of the same construction as those just described between this shaft and the lever 19; but the cams 54 and 56 for the lever 18 will of course be set at the proper angle, so that the frame 8 carrying the pusher bars 31 will be thrown forward by the lever 18 after the lever 19 has been actuated to put the blades 10 into their obstructing position, to prevent movement of any more of the cans from the trays 23 beyond the upright member 26.

The motor 15 is supported upon a plate 65 attached to one of the legs 2; and its shaft 66 may carry a pulley 67 joined by a belt or chain to the pulley 68 on a shaft 69 in the bearing 70, supported by the plate 65. The shaft 69 carries a smaller gear joined by means of a belt or chain 71 to a pulley wheel or other gear 72 on the shaft 16. The gearing connecting the motor 15 to the shaft 16 operates of course to reduce the speed of the motor and turn the shaft 16 at the right number of revolutions per minute.

The frame 8 comprises two sliding bars 73 connected at their rear ends by a cross-bar 74. These bars 73 move in guideways or grooves in the parts 7, and to the bars 73 are connected upright plates 75 to which are at-

tached longitudinal arms 76, one above the other.

These arms extend forward as shown in Figure 3, and support the cross-bars 31 at their front ends. The cross-bar 74 mounts bearings 77 to receive a shaft or pin 78 carrying an arm 79, connected to the lever 18 by a link 80. The arm 79 and link 80 may have a bolt and slot connection, so that the combined length of these two parts may be adjusted. The upright plates 75 may be connected by bars 81 encircled between the plates by tubular spacers 82. There will of course be as many pusher-bars 31 as there are tiers 15 of cans to be thrust into the boxes or cases on the table plate 36.

The machine, so built, will operate continuously and as long as the cans are fed to the chute 4, they will roll down into the trays 26; 20 arranging themselves in tiers to be delivered by the frame 8 to the boxes in which they are to be stored or shipped. The resilient and yielding connections between the shaft 16 and the levers 18 and 19 will prevent damage in 25 case of the wrong operation of the machine or in the event that any of the cans get slightly out of position. However, I provide in addition a clutch which is designed for normally disconnecting the shaft 16 from the 30 gear 72 which is loose on the shaft, so that, to cause actuation of the apparatus, the clutch must first be moved and held in position to put the shaft 16 and gear 72 into operative relation.

35 For this purpose I provide the front of the platform 1 with a bracket 83 adjacent to the legs 2 and this bracket mounts one end of a rock shaft 84. The other end of the rock shaft is supported in a bearing 85 adjacent 40 to the legs 3; and this shaft carries adjacent its middle part between one of the arms 9 an operating lever 86, which is fixed thereon so that movement of this lever 86 will turn the shaft. The lower end of this lever is attached to a trip push-bar 87 joined by a swinging link 88 to said arm 9; and there is a spring 45 89 attached to the arm 9 and the lever 86 and normally tending to move the bar 87 away from the platform 1. At its outer end 50 this bar 87 has a handle 90.

On the shaft 84 adjacent the bracket 83, is a trip lever 91, pinned to this shaft 84; and at the lower end of this lever is mounted a pin 92 having an enlarged head and encircled 55 by a spring 93 between this head and the end of the lever 91. The end of this pin may be riveted over so that it can not be separated from the trip-lever 91, but the spring 93 enables it to yield towards the lever 91 when it 60 is pressed to the right with reference to Figure 5. This pin presses against a clutch latch 94 pinned to a trip cam lever 95 at 96, the lever 95 being mounted on a pivot pin 97 supported from the frame 9 of the apparatus. 65 This trip cam lever carries a roller 98 which

runs upon the surface of the cam 99 having a number of projections; and the latch 94 may project above the pivot pin 96 and be connected at its upper end to the lever 95 by a spring 100. The free end of the lever 95 may be joined by a spring 101 to the pivot-pin of a clutch lever 102, this lever being pivoted at the lower end of the bracket 83, and between the pivot of this clutch lever 102 and a projection 104, on the bracket 83 is a compression spring 103. This spring engages the end of the lever 102 near the corner and normally acts on the lever 102 so as to tend to depress the free end thereof. The top of this clutch lever 102 is engaged by a stem or plunger 105 slidably mounted in a bracket 106 on the under surface of the table 111 and is forced down by a spring 107.

Cooperating with the gear-wheel or pulley 72 is a clutch collar 108 having a circular groove 109 to receive the end of the clutch lever 102. This clutch collar carries in a longitudinal bore a clutch pin 110 which is notched at 111 in its side and the clutch collar at one end carries a stop 112 to engage a spring 113 bearing on one end of the clutch pin 110. This spring normally throws the pin 110 towards the openings 114 in the hub of the wheel 72, and cam 99, which is affixed to the gear 72 and can rotate freely on the shaft 16. When the lever 102 is in the groove 109 and engages the notch 111 of the pin 110, the clutch 108 and gear wheel 72 are disconnected, so that the gear 72 and cam 99, which are loose on the shaft 16, can rotate freely on the shaft 16. This shaft is now stationary. Clutch collar 108 is keyed on the shaft 16. Hence the apparatus does not run, but whenever the shaft is to be connected, to set the apparatus into operation, the operator takes hold of the handle 90 and pushes the trip bar 87 inward. This action swings the arm 86, turns the shaft 84 and throws the trip lever 91 so as to press the pin 92 against the latch 94 and cause it when one of the projections of the cam 99 engages the roller 98 to be lifted by the trip lever 95, and thus raise the clutch lever 102 out of the groove 109 and release the pin 110. The clutch lever 102 may be recessed or have an opening therethrough from 110 its upper side to its lower side to receive the lower end of the latch 94, the two ends of this recess are indicated in Figure 5 by numerals 115 and 116; and whenever the lower end of the latch is pressed to the left (Fig. 5) 115 by the lever 91, it will engage an edge of this recess and raise the lever 102 to permit the spring 113 to shoot the clutch pin 110 into one of the openings 114 of the cam 99 and wheel 72. The power is now on and the wheel 72 turns the shaft 16. Hence by merely pressing forward on the push-bar 87, the power is connected to the shaft 16, and by releasing the push-bar, the springs 89, 100, 101, and 103 will restore the parts to their 120

125 position. The apparatus is now ready to receive the cans.

former inoperative position, and as soon as the collar carries the pin 110 up, the lever 102 runs into the notch 111, to pull pin 110 out of the hole 114 filled by it to disconnect the clutch collar 108 from the gear 72. Thus any time the stopping of the apparatus becomes necessary the mere release of the bar 87 by the handle 90 will suffice. Lever 102 may have a cam projection 117 on its under face to run in the groove 109 of the clutch collar 108. Hence when the operator lets go of the handle 90 the loading apparatus stops and requires continued pressure on the handle to keep it running. When the handle is not pressed, the action of the cam 99 on the lever 95 does not lift the lever 102, because the latch 94 does not catch the edge 115 of the opening in the lever 102. This lever thus stays down, its cam end 117 keeping pin 110 withdrawn. When the apparatus is operated, the release of the handle 90 at once allows the lever 102 to drop into the groove 109; and as soon as the pin 110 is carried by the clutch around to the lever it is pulled back and the clutch 108 and wheel 72 are then immediately disengaged. The whole machine then stops at once.

We claim:

1. Apparatus for loading sealed vessels into cases comprising a sloping platform having a receiving chute at its upper end and one or more receiving trays adjacent the lower end on which said vessels are passed from said chute, a blade for separating the vessels on each tray upon those arriving thereat, a pusher frame having a bar associated with each tray for discharging said vessels on each tray, a main shaft beneath the platform, connections comprising rocking levers to operate each blade and the pusher bar frame in succession, a clutch for connecting said main shaft to a source of power, parts for keeping said clutch normally in disconnected position, and parts comprising a push-bar adjacent one side of the frame and connected to control the clutch and enable power to be delivered to said shaft.

2. Apparatus for loading sealed vessels into cases comprising a sloping platform having a receiving chute at its upper end, a frame comprising one or more pusher bars at the rear of said platform, the top of the platform being also inclined toward said frame, a second frame having one or more separator blades adjacent the pusher bar frame, connections for operating the pusher bar frame and the second frame in alternation, a clutch comprising a parts normally disconnecting said frames from a source of power, and parts adjacent the platform for controlling the clutch to enable power to be supplied to the apparatus when desired.

3. Apparatus for loading sealed vessels into cases comprising a platform, a main shaft beneath said platform, a second shaft sup-

ported at the rear of the platform, a frame comprising one or more pusher bars to discharge vessels from said platform, and a second frame comprising one or more separator blades together with links mounted on the second shaft and connected to receive power from the main shaft and actuate said frames in succession.

4. Apparatus for loading sealed vessels into cases comprising a table and a pusher bar frame for discharging said vessels from said table, a main shaft beneath said table, a grooved clutch collar fixed on said shaft, a pin for said collar having a notch to coincide with said groove, a gear-wheel carrying a cam loosely mounted on the shaft the cam and gear-wheel having recesses to receive the clutch pin, a lever having an end shaped to prevent the pin from connecting the clutch to the gear-wheel, and means comprising a lever and a latch for moving the first-named lever out of position so as to permit the gear-wheel to be connected to the shaft by said clutch collar.

5. Apparatus for loading sealed vessels into cases comprising a table having a receiving chute, one or more trays to which said vessels are passed, a pusher frame for discharging said vessels from each tray, a main shaft connected to operate said frame, a clutch collar and gear-wheel on the shaft, the collar being fixed to the shaft and the gear-wheel loose thereon, the collar having a groove and a notched pin and the gear-wheel recessed to receive the pin to connect the gear-wheel to the shaft, a lever having an end shaped to enter the groove and keep the pin out of engagement so as to maintain the gear-wheel disconnected from the shaft, a push-bar mounted adjacent said table, and parts comprising an arm, a lever, a latch and cam to lift the first-named lever from the groove in the clutch collar and enable the gear-wheel to be connected to the shaft to transmit power thereto.

6. Apparatus for loading sealed vessels into cases comprising a table sloping from one end to the other, a can receiving chute at the highest point of the table, the table also inclining from front to back, a pusher bar frame mounted to move from the back of the table toward the front to discharge the vessels therefrom, a frame comprising a pair of uprights carrying one or more separator blades mounted at the back of the machine, pivoted levers connected to the pusher frame and the frame carrying said blades, a main power shaft beneath the table, and means comprising links and cams mounted on said shaft and connected to the levers to operate said blades and said pusher frame in succession.

7. Apparatus for loading sealed vessels into cases comprising a table having a receiving chute at one end, and a pusher bar frame and a frame mounting separator blades at the

rear of the table at the opposite end, a main shaft and connections for actuating said frames, a clutch for connecting the main shaft with a source of power, said clutch being normally disconnected, a rock-shaft extending along the front of the apparatus, an arm on said shaft, an operating push-bar connected to said arm, and parts comprising levers, springs, a latch, and a cam on said shaft acting upon said bar being pressed by the attendant to cause the clutch to connect said shaft with said frames.

In testimony that we claim the foregoing as our invention, we have signed our names hereto.

WILLIAM H. BROOKS.
